UNITED STATES PATENT OFFICE.

JONATHAN R. NAYLOR, OF KALAMAZOO TOWNSHIP, KALAMAZOO COUNTY, MICHIGAN.

CLOTHES-RACK.

1,125,372.

Specification of Letters Patent.

Patented Jan. 19, 1915.

Application filed February 24, 1914. Serial No. 820,471.

To all whom it may concern:

Be it known that I, JONATHAN R. NAYLOR, a citizen of the United States, residing at Kalamazoo township, county of Kalamazoo, and State of Michigan, have invented certain new and useful Improvements in Clothes-Racks, of which the following is a specification.

This invention relates to improvements in clothes racks.

The main objects of this invention are: First, to provide an improved clothes rack adapted as a wall attachment in which the rack proper may be lowered for placing the clothes upon the rack and drawn up to the desired position to be out of the way. Second, to provide an improved clothes rack which may be collapsed and when collapsed, occupies but little wall space. Third, to provide an improved clothes rack embodying these advantages, which is very easy to manipulate and of large capacity in proportion to its size.

Further objects, and objects relating to structural details, will definitely appear from the detailed description to follow.

I accomplish the objects of my invention by the devices and means described in the following specification.

30 The invention is clearly defined and pointed out in the claims.

A structure which is a preferred embodiment of my invention is clearly illustrated in the accompanying drawing forming a part of this specification, in which:

Figure I is a detail perspective view of a structure embodying the features of my invention, the same being shown mounted upon a wall and with the arms of the rack extended. Fig. II is a front elevation of my improved rack and its support, with the arms of the rack collapsed. Fig. III is a detail perspective view of the ceiling member 6 and the upper end of the support rod 1. Fig. IV is a detail view partially in vertical section showing one of the wall brackets 2 and the lower end of the support rod 1. Fig. V is a detail perspective view of the support rod 1 with support member 7 mounted thereon, the rack plate 11 being removed. Fig. VI is a detail vertical section on a line corresponding to line 6—6 of Fig. II. Fig. VII is a detail horizontal section on a line corresponding to line 7—7 of Fig. II. Fig. VIII is a perspective view of one of the wall brackets of Fig. II. Fig. IX is a

detail perspective view showing a wall bracket arranged at the upper end of the support rod in lieu of the ceiling member shown in Fig. III.

In the drawing, similar reference characters refer to similar parts throughout the several views, and the sectional views are taken looking in the direction of the little arrows at the ends of the section lines.

The frame of the support rod 1 is supported at its lower end by the wall bracket 2, having an outwardly projecting arm 3. The end of the arm is provided with a longitudinal slot 4. The support rod 1 is carried by the forked base 5, the end of said rod resting on shoulders provided thereon. Said base 5 is carried by the bolt 21 passing therethrough and having a head engaging the slotted end of arm 3. The bracket is provided with a downwardly projecting ear 22 slotted to receive the attaching screw 23. The ceiling bracket or member 6 is provided with a socket for the upper end of the support rod 1. The ceiling bracket 6 is provided with projecting arms 24 and 25 and is concaved on its upper side so as to more effectively engage the ceiling. In assembling, the ceiling bracket is placed upon the upper end of the support rod 1 and the wall bracket 2 is positioned on the wall with the base 5 engaging the rod 1. Then as the nut or bolt 21 is screwed up the rod will be raised to clamp the ceiling bracket in place so that it is not necessary to provide securing screws therefor.

In the modification shown in Fig. IX, the upper end of the support rod is supported by a wall bracket 2' provided at its outer end with a downwardly projecting arm 3' which at its lower end has the longitudinal slot 4'. The end of said rod is clamped in place by means of the clamping bolt 26. The support member 7 is provided with rearwardly and upwardly projecting arms 8 which embrace the sides of the support rod 1. The support member 7 is provided with rollers 9 arranged on opposite sides of the support rod. The front roller is arranged at the lower end of the support member 7, while the rear roller is arranged at the upper ends of its arms 8. This support member 7 is preferably a sheet metal stamping. The rack arms 10 are mounted upon the rack plate 11 by means of the pivots 12. The plate 11 has rearwardly projecting ears 13 which are engaged by

the spindle 14 of the lower roller which constitutes a supporting pivot for the plate 11. The rack plate is held in its extended position by means of the hook 15 which is adapted to engage over the front edge of the plate when the plate is raised to its horizontal position, as shown in Fig. I. The support member 7 is supported by means of the cord 16 which is arranged over the supporting pulley 17 carried by the arm 25 of ceiling member 6. One end of the cord is attached to an ear 19 on the upper end of the support, while the other end is attached to the ear 20 at the lower end of the support, as clearly shown in Fig. VI. The cord may be engaged in the slot 4 of the lower wall bracket 2 for securing it in its adjusted positions.

In the modification shown in Fig. IX, clamping bolt 26 for the support rod is provided with a hook 27 by means of which the pulley 28 for the cord 16 is supported. By using the wall bracket 2 at both ends of the support rod there is no necessity for providing the special ceiling brackets. The ceiling brackets are, however, desirable in that the rod can be secured without the necessity for climbing up to attach the wall bracket. The rack may be lowered to receive the articles to be dried and then drawn up out of the way. With the rack closed, as shown in Fig. II, the rack occupies comparatively little space and may be retained in this position so as not to interfere in any way with use of the room for ordinary purposes.

I have illustrated and described my improved rack in a practical embodiment. I have not attempted to illustrate or describe certain modifications I contemplate as I believe the disclosure made will enable those skilled in the art to embody my improvements as may be desired.

Having thus described my invention, what I claim as new and desire to secure by Letters Patent is:

1. In a clothes rack, the combination of the supporting rod, a wall bracket for the lower end of said rod, a support for the up-

per end of said rod, a pulley on said support 50 for the upper end of said rod, a rack comprising a plate having rack arms thereon, a support therefor having rearwardly and upwardly projecting side members embracing said rod, rollers on said support disposed 55 to engage opposite sides of the rod, the rear roller being disposed at the upper end of the rearwardly-projecting arms, the front roller being disposed at the lower end of the support, the spindle for the front roller 60 constituting the pivot for said rack plate, a hook on said support for supporting the rack plate in its erected position, and a suspending cord for said support arranged over said pulley on said ceiling member. 65

2. In a clothes rack, the combination of the supporting rod, a rack comprising a plate having rack arms thereon, a support therefor having rearwardly and upwardly projecting side members embracing said 70 rod, rollers on said support disposed to engage opposite sides of the rod, the rear roller being disposed at the upper end of the rearwardly-projecting arms, the front roller being disposed at the lower end of the support, the spindle for the front roller constituting the pivot for said rack plate, a suspending cord for said support, and a pulley over which said cord is arranged. 75

3. In a clothes rack, the combination of 80 the supporting rod, a rack comprising a plate having rack arms thereon, a support therefor, rollers on said support disposed to engage opposite sides of the rod the front roller being disposed at the lower end of 85 the support, a spindle for the front roller constituting the pivot for said rack plate, and means for raising and lowering said support, all coacting substantially as described for the purpose specified. 90

In witness whereof, I have hereunto set my hand and seal in the presence of two witnesses.

JONATHAN R. NAYLOR. [L. S.]
